UNITED STATES PATENT OFFICE.

ARTHUR H. STURGES, OF OMAHA, NEBRASKA.

TUBULAR FIRE ESCAPE.

Application filed October 15, 1923. Serial No. 668,703.

To all whom it may concern:

Be it known that I, ARTHUR H. STURGES, a citizen of the United States, residing at Omaha, in the county of Douglas and State 5 of Nebraska, have invented certain new and useful Improvements in Tubular Fire Escapes, of which the following is a specification.

The present invention relates to fire escapes, and particularly to a fire escape of 10 the tubular type.

The present application is a companion to the application Serial No. 668,704, filed by the present applicant of even date herewith 15 and entitled Doors for tubular fire escapes.

An object of the present invention is to provide a fire escape with a novel construction of entrance which may be closed when not in use, and which at the same time will 20 comply with the various fire regulations and laws of the several States.

Another object is to provide a tubular fire escape with improved means for assisting persons into the tube proper, and which 25 means is adapted for use with persons of various sizes.

A further object of the invention is to provide a fire escape with closure doors at its entrance opening which effectually close 30 the opening against drafts and which have means to prevent the opening of the doors either from within the tubular member or from the exterior of the tubular member, and which at the same time provides operating means for releasing the doors from 35 a position within the building, and without requiring any special means such as keys, tools or the like and which may be actuated with ease at times of excitement, such as during 40 a fire, and may be operated even though persons may be jammed against and about the exit opening.

The invention further aims, in a tubular fire escape, at an improved locking means 45 which is simple in construction, which is visible at all times and is fool proof and which may be easily operated by any one who is capable of reaching to the desired height to grasp the operating lever.

A further object of the invention is to 50 provide a tubular fire escape with means whereby rain, water, snow and the like cannot enter the interior of the tube through its several joints and cannot gain access to 55 the working parts of the device.

The present device is adapted particularly for installation upon schools and like buildings for the protection of the children against fire and to insure the rapid and easy exit of the children in case of danger of fire, 60 and to also provide a device which may be safely used as an amusement for the children during fire drills to thus benefit from the point of interest and amusement as well as protection and to increase the interest of the 65 children in their studies and other duties incident to their attendance at school.

A still further object of the invention is to provide an improved support for a tubular fire escape for maintaining it at an 70 inclination of substantially 30 degrees to the horizontal or ground line as this inclination has been found by actual experimentation to be most desirable as it prevents the persons using the fire escape from moving too 75 rapidly through the tube and at the same time empties the tube as rapidly as possible with due care to prevent jamming or clogging of the tube during use.

A still further and important feature of 80 the invention is to provide a tubular fire escape with an entrance section adapted to receive persons one at a time and to so dispose and mount a bar in the upper portion of the entrance and intermediate the sides 85 thereof, said bar being sloped into the entrance opening and downwardly for accommodating persons of different heights and for facilitating the advancement of the persons in the tube without unnecessary delay 90 in properly adjusting themselves for the descent.

With the foregoing and other objects in view, the invention will be more fully described hereinafter, and will be more particularly pointed out in the claims appended hereto.

In the drawings, wherein like symbols refer to like or corresponding parts throughout the several views,

Figure 1 is a side elevation, partly in section, of a tubular fire escape constructed according to the present invention and as applied to the wall of a building, the full lines showing the device arranged rectilinearly, and the dotted lines showing the direction in which the tube may be curved.

Figure 2 is a detail side elevation of the door releasing lever at the entrance opening of the tube.

Figure 3 is a front elevation of the same. Figure 4 is a rear elevation thereof.

Figure 5 is an edge view of a bracket plate for supporting said releasing lever.

5 Figure 6 is a front view of the same.

Figure 7 is a rear elevation of the bracket plate.

Figure 8 is a front elevation of the strengthening frame for the entrance section of the fire escape.

10 Figure 9 is a vertical section taken through the same on the line 9—9 of Figure 8.

Figure 10 is a rear elevation of the frame.

15 Figure 11 is an edge view thereof.

Figure 12 is a fragmentary enlarged elevation, partly in section, of the entrance portion of the fire escape showing one of the doors closed.

20 Figure 13 is a detail front elevation of a pair of doors which may be used for closing the entrance section.

Figure 14 is a transverse section taken horizontally through the same on the line 25 14—14 of Figure 13.

Figure 15 is a plan view of a metal threshold which is used at the bottom of the doors.

Figure 16 is an edge view taken at one 30 end of the threshold.

Figure 17 is a transverse section through the threshold on the line 17—17 of Figure 15.

Figure 18 is a detail enlarged view of 35 one of the upper hinge bolts of the doors.

Figure 19 is a fragmentary top plan view of the reinforcing frame with a door mounted therein and showing the attachment of the spring for normally urging the adjacent door to open.

40 Figure 20 is an inner side elevation of a wooden frame for mounting in the wall to support the reinforcing frame of Figure 8.

45 Figure 21 is a vertical transverse section through the frame mounted in the wall.

Figure 22 is a front elevation of the entrance to the fire escape, with the doors closed and showing the adjacent floor structure in section.

50 Figure 23 is a detail top plan view of the entrance portion of the fire escape, showing the support and mounting for the door opening lever and the hand rail or guide and adjacent parts.

Figure 24 is a plan view of a coupling ring employed between the sections of the fire escape.

60 Figure 25 is a transverse section through the same taken on the line 25—25 of Figure 24.

Figure 26 is a fragmentary end elevation of the lower portion of the fire escape as mounted against the wall.

65 Figure 27 is a detail side elevation, partly

in section, of adjacent sections or portions of the fire escape in position to be clamped together, and

Figure 28 is a side elevation of a building having a fire escape constructed according to the present invention applied thereto, the fire escape being slightly modified by the inclusion of an elbow in the upper end thereof to impart a substantially right angular turn to the tube.

75 The tubular fire escape of this invention is adapted to be mounted exteriorly of a building and to lead from a window, a door or other suitable opening formed in the side wall of the building at a point above the ground.

According to the present embodiment, the fire escape is provided with an upper or entrance section 30 which preferably flares from its lower circular end into a vertically enlarged rectangular opening, and the enlarged upper end of the section 30 is adapted to fit into an opening 31 formed through the wall 32 of the building. The section 30 at its upper end is reinforced by a frame 33 which is preferably of angle iron cross section as shown in Figures 8 to 11, and which has the bottom rail 34 thereof turned reversely to the major portion of the frame so as to engage over a cross bar 35 which is mounted in the opening 31. The frame 33 is provided at opposite sides with pairs of attaching ears 36 and the frame 33, which is preferably of metal, is fitted into a wooden frame 37, shown in Figure 20 and 100 this wooden frame 37 is built into the opening 31 of the wall 32.

75 The side rails of the frame 37 are provided at suitable intervals with notches 38 to receive the ears 36. The ears have suitable openings therethrough for the reception of screws or other attaching devices to secure the metal frame 33 within the wooden frame 37.

80 The top portion of the wooden frame 37 forms a lintel 39 adapted to support the adjacent row or rows of bricks in the wall, and shingles 40 or the like may be packed into the opening 31 of the wall about the frame 37 to properly plumb or line up the frame to 110 support the entrance section 30 of the fire escape. The metal frame 33 is substantially of the size of the entrance opening and is adapted to carry a pair of doors 41, and each door 41 is provided, as shown in 115 Figures 12, 18 and 19 with a hinge bolt or pin 42 secured at its lower end to a bracket plate 43 which is screwed or otherwise suitably secured to the edge of the door 41. The pin 42 extends upwardly from the door 41 120 and through a suitable opening in the top rail of the frame 33. The upper end of the pin 42 has a longitudinal slot 44 extending transversely through the pin, and the latter is externally threaded at its upper end to 125

130

receive a nut 45. A coil spring 46 is placed about the upper end of the pin 42 and has a looped end 47 fitted in the slot 44 and held therein by the nut 45. The lower end of the 5 spring 46 has an arm 48 which is arranged to extend across the top rail of the frame 33 and provided with a depending finger 49 adapted to project downwardly against the remote side of the frame. The spring 46 is 10 arranged to normally urge the doors 41 into open position. The doors may be held closed by a lever 50 which is of angular formation as shown in Figures 1 to 4 and which is mounted in a bracket plate 51 secured in 15 front of the frame 33 and which has a vertical slot 52 through which the lever 50 extends. The angle portion of the lever is pivoted on a pin 53 which is mounted in the pair of lugs 54 projecting from the rear face of 20 the plate 51.

The lever 50 is provided near its upper end with an arm 55 to which one end of a spring 56 is attached, the other end of the 25 spring being secured by a bolt 57 or the like to the top of the entrance section 30 for normally drawing the lever 50 into upright position. The inwardly projecting end of the lever is provided with a downwardly extending arm 58 which has a T-head 59 in the opposite branches of which 30 are mounted set screws 60 one for each door 41, the set screws being adapted to engage, adjustably against the outer sides of the doors to hold them closed against 35 the tension of their springs 46. The upper end of the lever 50 is forked as at 61 to straddle a slide bar 62 which has one end mounted in a socket 63 formed upon the 40 upper end of the bracket plate 51, the slide bar 62 being curved downwardly and projecting into the receiving section 30.

The bracket plate 51 is mounted intermediately over the frame 33 so as to be substantially over the central portion thereof 45 and to dispose the T-head 59 across the space between the doors 41, and the rail 62 is also positioned intermediately of the door opening and is adapted to pass through complementary notches 64 formed in the 50 adjacent edges of the doors 41. Flexible packing strips 65 are preferably carried upon the doors and suitably notched to snugly engage against the opposite sides of the rail 62, the packing strips 65 being relatively flexible and adapted to give or bend 55 as the doors are swung into open and closed positions. The rail 62 is supported at its inner end upon a bolt 66 or the like which extends inwardly through the top of the 60 receiving section 30. A reinforcing strip 67 of relatively heavy metal, or the like, is secured along the upper side of the receiving section 30 and is adapted to receive the bolt 66 therethrough. This strip 67 is adapted 65 to reinforce the receiving section and sup-

port not only the same but also the hand rail 62 and adjacent parts.

The bracket plate 51 is provided upon its front face with a pair of spaced apertured ears 68 adapted to receive a transverse pin 69 therethrough, the pin being adapted to engage across the front of the opening lever 50 so as to prevent the same, as shown in Figure 2, from being swung downwardly to release the doors 41. The spring 56 and the adjacent parts are arranged between the top rail 39 of the wooden frame and the top wall of the receiving section 30, sufficient space being provided therefor as shown in Figure 1.

The parts are further enclosed by a cover board 70 which is fitted between the section 30 and the top rail 39, and which is arranged behind rows of bricks 71 which may be filled in or built up between the top of 80 the opening 31 in the wall and the top of the receiving section 30.

At the bottom of the metal frame 33 is mounted a metallic threshold 72 comprising a flat plate as shown in Figures 15, 16 and 17 with a relatively long connecting strip 73 at its inner edge, the strip 73 being adapted to seat upon the bottom rail 34 of the metallic frame. This strip 73 has at opposite ends depressions or sockets 74 for receiving the lower ends of pivot pins 75 carried by means of brackets 76 upon the lower corners of the doors 41. These pins 75 are therefore adapted to support the weight of the doors as well as to anchor the lower 100 corners thereof from swinging out of line with the top bolts 42.

As shown particularly in Figures 1, 21 and 22, the wall 32 has in its opening 31 a joist stringer 77 which abuts the ends of the 105 joists 78 for supporting sub-flooring 79 upon which the finished flooring 80 is placed. The threshold 72 sets upon the finished flooring 80 and projects into the frame 33. As shown in Figure 22 the base board 81 extends up to the wooden frame 37 and side casings 82 are bolted or otherwise suitably fastened to the frame 37 and provided with a cap 83 which extends across the upper portion of the frame 37 and encloses the 115 chamber between the wooden frame and the top of the entrance section 30 as shown in Figure 1, and also serves as a support for the bracket plate 51. The joists 78 support laths 84 to which finished plaster 85 is secured, this construction prevailing not only in the ceiling as shown in Figure 2, but also in the side walls about the wooden frame 37. The term "wooden frame" has been used to 120 contradict the outer frame from the inner frame 33 and it is to be understood that this frame 37 may be of metal or of other suitable material to comply with various building and fire regulations.

The lower rounded end of the receiving 130

section 30 is welded, or merges, into a flat ring 86 which is provided with an attaching band 87 suitably secured upon the outer side of the ring 86 by welding or any other suitable method. The attaching band 87 has an outstanding apertured flange 88 through which clamping bolts 89 are secured for connecting the various sections of the fire escape together.

10 As shown particularly in Figure 27, the body portion of the fire escape is composed of any desired number of tubular straight sections 90 which are upset at opposite ends to form out-turned flanges 91 behind which 15 are seated annular bands or rings 92 having out-turned flanges 93 which correspond to the flange 88 of the entrance section 30. The flanges 93 are also apertured to receive the clamping bolt 89 therethrough, and when 20 the bolts are drawn taut the outstanding flanges 93 and 88 are drawn together and clamp and compress the adjacent ends of the sections together for sealing them. Any 25 suitable asbestos or other fire proof and sealing cement may be packed into the joints between the flanges 93 and 88 for the purpose of excluding rain water and other accumulations which tend to rust out the joints and which would otherwise seep into the 30 interior of the fire escape.

As shown in Figure 28, where it is necessary to turn the fire escape into substantially parallel relation with a wall so as to lie close to the wall for economy in space 35 and also to obtain support from the wall, an elbow 94 is used which is built up of segmental sections, as is common in pipe construction, and the elbow or curved section 94 is provided with the clamping bands and 40 flanges in the same manner as are the body sections 90 of the fire escape.

The fire escape is provided at its lower end with an exit or landing section 95 the major portion of which is tubular and 45 adapted to be supported in a horizontal position upon a suitable base 96 of concrete or the like and which is reinforced at its open end by a channel ring 97.

The exit section 95 at its inner end is provided with a pair of angle sections 98 and 50 99 which are seamed together and to the inner end of the body of the exit section, and which have their lower walls 100 and 101 consecutively extending at increasing angles 55 from the bottom of the inclining fire escape body portion into the horizontal exit section 95. It will be noted that the exit section 95 is of greater height than the body portion of the fire escape and therefore is 60 substantially oval in cross section with the major axis extending vertically. The upper walls 102 and 103 of the angle sections 99 and 98 are diverged relatively to the lower walls 100 and 101 so as to merge the angle

sections 99 and 98 gradually into the exit 65 section 95.

The lower end of the entrance section 30 is preferably supported against the wall 32, and for this purpose a brace 104 is attached to a lower bolt 89 and the brace has a turn 70 buckle 105 therein by means of which the brace may be extended and contracted. The brace has a foot piece 106 which bears against the outer face of the wall 32 and which has a spur 107 adapted to engage between adjacent layers of brick as shown in Figure 1 to hold the foot piece 106 from slipping downwardly against the wall.

The turn buckle 105 may be adjusted so as to bring the spur 107 into registry with a 75 crevice in the wall, and the turn buckle may then be further adjusted for expanding the brace and binding the same between the wall and the lower end of the entrance section 30, to rigidly support the latter.

As shown in Figures 1 and 26, the body portion of the fire escape may be supported upon an adjoining wall 108 which extends at right angles to the wall 32 by a bracket including a hanger strap 109 secured at its 80 upper end upon a bolt 110 which is mounted in the wall 108 with its head innermost and an anchoring plate 111 on the bolt 110 against the head thereof. The lower end of the hanger 109 is connected to a compression 85 member 112, which may be of any suitable construction to impart strength to the member 112, by a bolt 113 which passes through downturned flanges 114 and 115 carried respectively by the hanger strap 109 and the 90 compression member 112. The bolt 113 also receives thereon out-turned ears 116 which form the ends of a split ring 117 which is fitted about the body portion of the fire escape for suspending the latter from the 95 bracket. The compression member 112 has a 100 foot flange 118 which bears against the outer face of the wall 108 and which is held from sliding thereon by a lag screw 119 or the like, as but little resistance is offered by the 105 compression member.

Of course various other devices than as shown may be incorporated in the wall structure and associated with the parts of the fire escape, such as a lintel 120 arranged 110 over the top of the entrance section 30 for supporting the outer rows or layers of brick or the like which form a part of the wall 32 and which may be fitted in place after the fire escape has been installed.

From the foregoing it is thought that the operation of the device will be apparent for when it is desired to use the fire escape all that is necessary is to remove the pin 69 and draw the lever 50 downwardly and inwardly, 115 the motion being a natural one so that when persons are in a crowded and excited condition of mind any movement of the lever 50

will tend toward the release of the doors 41 by the head 59 of the lever 50, which projects downwardly in back of the doors to normally hold them closed by the spring 56 against the tension of the door springs 46. This head 59 is relatively short and is moved upwardly in a slot 122 in the top of the entrance section 30 so as to clear the upper edges of the doors 41. The head 59 of the operating lever may be adjusted, by means of its set screws 60 to bind against the doors and take care of inequalities of the installation of the doors and other parts about the fire escape so as to insure the proper closing of the doors when the same are not in use.

When the lever 50 is, therefore, drawn down at its outer end the doors 41 are freed, and the springs 46 of the doors swing the same into open position as shown in Figure

1. The persons may now grasp the central hand rail 62 and swing themselves forwardly into the entrance section 30 and into a sitting posture and thus slide down through the tube or chute. As the hand rail 62 is inclined downwardly as shown in Figure 1, the rail may be readily grasped by large and small persons, such as by children of different sizes when leaving a school room or the like, and the inclination is such that the persons may readily accommodate themselves to the tube from different portions of the hand rail depending on the height of the person.

The sections 99 and 98 at the bottom of the fire escape gradually decrease the angle of inclination and thus automatically and gradually bring the persons into a state of rest in the exit opening. This prevents any violent precipitation of the persons from the end of the tube which would result in injury, particularly to small children.

I do not wish to be restricted to the size, form, and proportions of the various parts, and obviously changes could be made in the construction herein described without departing from the spirit of the invention, it being only necessary that such changes fall within the scope of the following claims.

What is claimed is:—

1. In a fire escape, a body portion adapted to be mounted at an opening in a building, a pair of doors hinged at opposite sides of the opening and arranged to swing into the body portion of the fire escape, and a bar disposed substantially in alignment with the entrance to the fire escape and projecting through said doors, said bar being supported at one end above the doors and at its other end having connection with said body portion beyond the doors.

2. In a tubular fire escape, an entrance section adapted to be secured to a building at an outlet thereof, a door normally closing said outlet, and a hand rail arranged centrally in the upper part of the outlet and

extending through said door, said door having an opening therethrough for the passage of said hand rail and the opening extending through the edge of the door whereby the latter may be opened and closed without interference from the hand rail.

3. In a tubular fire escape, an entrance section adapted to be secured to the wall of a building at an outlet, a pair of doors closing said section, releasable means for holding said doors closed, and a hand rail arranged centrally in the upper part of said entrance section and inclined outwardly and downwardly from the wall of the building, said doors having recesses in their free edges for the passage of the hand rail therethrough and to permit of the operation of the doors without interference from the hand rail.

4. In a tubular fire escape, an entrance section adapted to be secured to a building at an outlet thereof, a pair of doors hinged at opposite sides of the entrance section and normally urged into open position, a releasable retaining lever adapted for normal engagement with said doors to hold the same closed, a hand rail extending downwardly from a point above the entrance section and being curved into the section and inclining downwardly therein for grasping by persons entering the fire escape, said doors having slots in the free edges thereof through which the hand rail is adapted to extend, a flexible sealing device carried by the doors and extending over said slots for yieldingly binding about the hand rail to seal the opening thereabout in the doors.

5. In a tubular fire escape, an entrance section adapted to be secured to a wall at an outlet thereof, a pair of doors hinged to the entrance section, springs connected to said doors for normally swinging the same outwardly into the entrance section, a spring pressed lever pivoted over the entrance section with an angle portion at the inner side of the wall and having a heel portion arranged to engage against the outer sides of the doors for maintaining the same closed, means for releasably locking said lever from swinging into releasing position, and a hand rail mounted in the entrance section extending inwardly through the wall and through the doors and being curved upwardly toward said lever.

6. In a tubular fire escape, an entrance section adapted to be mounted through an opening in a wall, a pair of doors hinged in the opposite sides of the section, springs connected to the doors for normally swinging the same into open position, a bracket plate arranged above the entrance section and centrally thereof, a lever pivoted in the bracket plate with an angle portion extending inwardly from the wall and having a heel portion extending outwardly and down-

wardly for engagement with the outer sides of said doors to hold the same closed, a spring mounted on said section and connected to said lever for normally holding the same against said doors, said bracket plate having a pair of outstanding apertured lugs at opposite sides of the hand portion of said lever, a removable pin carried in said lugs for locking the lever against swinging movement, and a hand rail secured at one end of said bracket plate and being

curved downwardly into said entrance section and extending centrally into the upper portion thereof and diverging upwardly from the bottom wall of said section.

15

In testimony whereof, I have affixed my signature in presence of two witnesses.
